ware

Application March 14, 1935, Serial No. 11,142

15 Claims. (Cl. 95—6)

My invention relates to improvements in methods for making blue prints. In developing such prints water is used, resulting in so-called bleeding, i. e. discoloration of the white areas by the blue coloring material. My invention is directed more particularly to the substantial elimination of this bleeding or running of the color.

As pointed out in Patent 1,861,298 which issued May 31, 1932, based on my application filed May 10 11, 1931, the sensitized coating of the usual blue print is applied as a solution containing mixtures of potassium ferricyanide and organic salts of iron such as ferric ammonium oxalate. During the period of exposure to such light the potassium ferricyanide is partly reduced to potassium ferrocyanide while the ferric ammonium oxalate is reduced to ferrous ammonium oxalate.

After exposure, the paper is washed with clear water which removes all the unexposed soluble chemical from the areas which were behind the opaque portion of the tracing or negative and also removes the loose exposed or reduced chemical, i. e. that portion which does not adhere to the fibres of the paper. This washing, in a certain sense, also starts the process of oxidation of the reduced chemical which action is necessary in the formation of the blue lines or areas. In other words, if left long enough in the water the so-called "potash" treatment hereinafter referred to, is unnecessary. It is the practice, however, to complete the oxidation by applying bichromate of potash or some other strong oxidizing agent to the surface of the paper immediately after the application of the first water wash. The excess bichromate or "potash" must be washed off the surface by applying a second water wash, after which the paper is ready for drying.

Prints made in this manner are far from satisfactory or dependable when first class blue prints with clear white lines or blue line prints on a clear white background are desired. The difficulty is caused by the fully exposed chemical in certain areas running down into adjacent white or nonexposed areas as soon as water is caused to flow over the surface of the paper, thus staining the white areas blue or making the white lines too narrow and in other ways detracting from the appearance of the prints, i. e. those having white lines on a blue background and those having blue lines on a white background, particularly the latter.

My earlier method for overcoming these difficulties, as described in said patent, involves the use of a special developer before applying any

water to the print, and is successful even when the blue printing machine is operated at a comparatively high rate of speed. One method of my present invention obviates the use of a special developer, requiring merely the application 5 of water, except, of course, for the subsequent application of the usual fixing bath or "potash" which completes the oxidation. The new process has the advantage, therefore, that it follows the general sequence heretofore employed for years 10 in making blue prints, except for an additional preliminary water treatment of a special character, and, furthermore, the equipment used may be very similar to standard continuous blue print machines except for a few attachments and in- 15 incidental alterations.

The object of the invention is to provide a new and simple method of overcoming the difficulties due to running and bleeding heretofore inherent in the use of liquid in developing photo-copies 20 or prints.

A contributory object is to provide a method for applying liquid to the side of the sheet opposite the one having the light sensitive coating thereon whereby the required reaction is made 25 possible by the fact that the said liquid works its way through the sheet from the back to the front.

Another object is to provide a method for applying water to the uncoated surface of a sheet 30 of blue print paper to cause absorption of said water by said sheet and start the oxidation of the chemicals comprising the coating.

In the accompanying drawings I have illustrated several embodiments of the mechanical 35 features of the invention in the form of attachments to well known types of so-called continuous blue printing machines, capable of carrying out the method. The invention may be embodied in other forms, however.

Fig. 1 is a side elevation of part of a blue printing machine;

Fig. 2 is a side elevation of a modified form of the invention;

Fig. 3 is a side elevation of a further modification;

Fig. 4 is a side elevation of an additional modification; and

Fig. 5 is a side elevation of a further modification.

Referring to Fig. 1, the operation of the machine as a whole will be described briefly. The sensitized paper is fed through the machine from a roller, passing rearwardly and upwardly past a source of light, with the necessary tracings or 55

negatives held against said sensitized surface whereby the printing is accomplished. The span of paper thereafter continues its travel toward the rear of the machine, passing up and down over various rollers. The first application of water is made by passing said span of paper under one of said rollers which is being continuously sprayed with water, this roller making contact with the back or unsensitized side of the paper, whereby the moisture thus applied soaks through the paper reaching the chemical on the coated side and causing an initial oxidation. The paper then continues its travel, passing through the usual water wash which washes off the superfluous chemicals but without causing bleeding or running, after which the paper, as it continues its travel, is treated to an application of potash or other oxidizing agent, following which it passes through the drier and is then ready to be cut up into prints of the desired size.

Referring now to Fig. 1, the machine shown therein comprises a suitable frame 10, having a supply of blue print paper in the form of a roll mounted on a rod 11 near the front of the machine. The paper is drawn from the roll in the form of a span 12 which passes rearwardly over a horizontal portion or table and thence upwardly past a curved sheet of glass 13, past a row of arc lamps 14, or other suitable source of light. Said paper then passes over rollers 15, 16 and down under tension roller 17, the shaft 18 of the latter being mounted in suitable, vertically adjustable bearings, not shown, which, however, are supported on a chain 19 whereby the paper is maintained under the proper tension. From the tension roller the paper passes over the roller 20, down under the roller 21, over the roller 22 and under the moistening roller 23 and also past roller 24. The last three rollers as a group cause the paper to travel in a V shaped span, whereby the moisture may be applied to the rear side thereof, i. e. the coated side faces downwardly. Prior to reaching this group of rollers, no water is applied to either side of the paper. The water at this point is supplied through a pipe 25 from which it is sprayed onto the roller 23 with the result that puddles are formed on the paper, one on each side of the roller, the water which collects in said puddles running off from both ends without contacting with the sensitized surface or under surface of the paper, and is discharged in any suitable manner. Throughout this figure of the drawings the reference 12, indicating the span of paper, is applied to the sensitized side from which it will be seen that the arrangement of the rollers 21, 22, 23 and 24 is for the further purpose of turning the paper upside down with reference to its position as it enters the machine initially and in general as it travels rearwardly.

The application of moisture to the back of the paper at this point in its travel is the important feature of the invention as the water is permitted to soak through the paper for a long enough period for oxidation to take place before the paper enters the conventional water wash at the top of the unit, as hereinafter described.

Heretofore, water has not been applied to the back of paper as it passes through a blue print machine except for preventing curling of the paper stock after the print has passed the usual water wash where the water is applied to the front or coated surface of the print. My improved method differs from the prior practice in applying moisture to the back of the print in

advance of the application of water to the coated side of said print and in applying it in such a way that it may soak through the paper and reach the chemical from the rear.

With the particular arrangement described herein, the water which runs off from the edges of the paper is caught by a suitable V shaped pan 26, surrounded by another tank 27, provided with a suitable outlet. In order to adjust the operation of the machine for the different speeds at which the paper may travel and to afford the necessary time for the moisture to soak through the paper before it reaches the usual water wash at the top of the unit, the supporting frame 28 for the three rollers 22, 23 and 24 may be adjusted vertically on suitable supports 29.

The water wash at the top of the unit is indicated generally by 30 and comprises rolls 31, 32 and 33, around which the paper passes and at which point it is washed by water delivered in a spray from pipe 34 against the roller 32. An additional back wash 35 may be applied to the sheet as it descends over the roller 36, to prevent curling at the edges, this being common practice. The paper then passes under roller 37, 25 on shaft 38 near the bottom of the machine, and thence rearwardly to the potash station and to the drier which may be any suitable or well known construction and is not described herein.

Referring again to the application of moisture to the rear of the print before it reaches the conventional water wash, I have found that if warm water is used the oxidation process is greatly accelerated. Thus the pipe 25 may be connected to a suitable source of warm water. 35

I have also discovered that the oxidation process is hastened by applying to the front or sensitized side of the paper heated water vapor in small amounts. This vapor is applied in the vicinity of the roller or whatever device is employed for applying moisture to the back of the paper, the vapor preferably being applied simultaneously with the application of moisture to the back. This eliminates the necessity for a lengthy soaking period between the initial application of moisture and the conventional water wash applied to the front of the paper. 45

By applying water to the rear of the paper prior to washing the front as in the method disclosed herein, oxidation appears to be started with the chemicals that are deeply imbedded in the fibers of the paper prior to removing any chemical from the surface of the paper. This brings about a better blue print with deeper color from the same light exposure. This is probably due to the fact that if running water is first applied to the coated side of the sheet, the washing action or force of the water removes not only the outer layer of completely reduced insoluble chemical but also a certain portion of the incompletely reduced chemical buried in the fibers of the paper stock. This partially reduced chemical is capable of producing some of the insoluble blue substance which is Turnbull's blue, if it is allowed to oxidize. The running water, as explained, removes the partially reduced chemical before it has time to oxidize, whereas by applying the water to the back of the sheet, the chemical is moistened enough to start oxidation but with no tendency to remove it or mechanical action to remove it. This initial step as thus described may be termed a soaking process or step. 60

In hastening the oxidation process by the use of moisture laden air, it is not necessary to sup- 75

ply the vapor in the form of steam. The vapor may be supplied from any suitable source, either that arising from the warm water issuing from the pipe 25 or through a spray pipe 39, supplied for that purpose. With this double application of moisture to the front and rear of the paper, the moisture from the rear does not have to penetrate the entire thickness of the paper in order to oxidize the outer layer of the chemical. It is evident that either method may be used singly and that the combination of the two assures good results on high speed continuous blue printing machines.

In Fig. 2 the printing portion of the machine may be assumed to be the same as that previously described. The span of paper 12, after leaving the tension roller 17 (the same as in Fig. 1) passes upwardly and over a water tank or trough 40, during which passage moisture is applied to the back thereof, the coated surface being at the top. The paper passes over spaced rollers 41, 41 and a middle roller 42 which latter dips into said trough 40. As shown in dotted lines, one of the rollers 41 is mounted on adjustable arms 25 43 to elevate the span of paper above the roll 42. The trough is kept full of water from the reservoir 44. The roll 42 may be rotated in either direction, i. e. with or against the direction of travel of the paper, depending on whether more 30 or less moisture is desired at the under surface of the same. From this initial moistening equipment the span of paper may pass directly to the usual water wash, or, in the case of paper traveling at a high rate of speed, a second application 35 of water to the rear thereof may be desirable. In such cases a second trough 45 is provided with a roller 46 dipping therein and auxiliary rollers 47, 48, somewhat similar to those previously described. The roller 48 may be mounted on an 40 adjustable arm 49 to permit elevation of the span of paper above the roller 46 and thus avoid sticking when the machine stops.

Said water wash, indicated generally by reference 50, may be similar to that previously described in connection with Fig. 1.

In Fig. 3 another modification is shown in which the span of paper 12, after leaving the printer, passes a moistening roll 51, which, with its adjuncts, is the same as what is shown in Fig. 1, whereby moisture is applied to the rear surface of the paper. From this location the paper passes over idle rollers 52 and under rollers 53, 53, traveling in a horizontal span, coated side down, through a water bath in the tank 54. The water is maintained at a constant level by overflow pipe 55, and the paper, as it becomes saturated and expands, is prevented from wrinkling by passing under curved or bowed bars 56, in a manner well understood in the art. The water in this tank is not violently agitated but is comparatively still. The excess chemical which falls from the paper descends in the tank and is not carried along the surface in a way that would cause bleeding. Also, the initial application of 60 water to the rear of the paper further insures against bleeding. From this tank the paper passes to the usual water wash, indicated generally by reference 57, which will be understood from the previous description of similar devices 65 for washing the front of the print.

In Fig. 4 I have illustrated a modification of a different type, which might be said to involve a method of blotting the sensitized surface with moist, absorbent material after exposure, to withdraw the chemicals which it is desired to re-

move from the coated surface and to supply the necessary liquid. If this absorbent pad or blotter is pressed firmly against the surface of an exposed blue print for a few seconds, without sliding the pad along said surface, it will be found upon removal that the unexposed areas are white or practically free from the unreduced chemical and that on the exposed portion of the print not only the loose outer layer of ferrous compound has been removed but oxidation has 10 started sufficiently to prevent bleeding or running of the color when the print is subsequently subjected to the regular treatment with running water or a water bath.

In this apparatus the band of blue print paper 15 12, after issuing from the printing section as heretofore, passes under a tension roller 17, thence upwardly over an idle roller 58 and down under rollers 59 and 60, upwardly and over roller 61 near the top of the frame of the attachment 20 and thence downwardly around larger roller 62 which is mounted on a suitable shaft 63.

The material for accomplishing the blotting or absorbing action is, in this case, a moist endless belt 64 of suitable material such as felt, which 25 belt passes around rollers 65, 66, mounted near the main roller 62, said belt passing downwardly around rollers 67 and 68, which latter are mounted in a container or tank 69. The roller 67 is mounted on a pivoted arm 70 provided with a 30 spring 71 which maintains suitable tension on the endless belt. The latter, it will be seen, is caused to bear against the coated side of the sheet of blue print paper 12 where it passes around the roller 62 and is held in firm contact therewith, without slippage, for more than half of the circumference of the roller 62. The length of the path 35 of travel of the moist absorbent belt while it is in contact with the blue print, may be varied by adjusting the arm 72 on which the roller 66 is mounted, said arm being mounted to swing about the axis of the shaft 63. The span of paper has its coated side 12 uppermost as it leaves the printer and passes under the tension roller 17, one of the purposes of the additional rollers between 40 said tension roller and the main roller 62 being to turn the paper upside down during its travel so that its coated surface may be brought in contact with the absorbent belt as both spans pass around said main roller.

It is necessary to wash from the absorbent belt the chemicals which adhere thereto while it is in contact with the exposed surface of the blue print paper, and for this purpose said belt is passed through a water bath in the tank 69. The descending span is washed with water by means of a spray issuing from the pipe 73, the water being applied to the side of the belt which was in contact with the blue print. This tends to wash the chemicals from the belt, which washing is further accomplished as the latter passes through the water bath in the tank, the level of the water being maintained by a suitable overflow pipe 74. If desired, a revolving brush or brushes such as 55 75 may also be employed to aid in removing any surplus chemical from the belt. If the chemical were not removed it would, of course, be brought into contact with the surface of the print during the continued travel of the endless belt around the main roller and would stain the blue print, 60 due to the chemical reaction which would take place.

After the blue print paper leaves the main roller 62, it passes through a conventional water wash, indicated at 76, but without any bleeding 75

or running of the color and is thereafter fixed and dried in any suitable manner.

In Fig. 5 a modification of the means for pressing the absorbent material against the span of blue print paper is illustrated. In the attachment just described the paper passes around a roller with its coated and exposed side outwardly, an endless belt of absorbent material being pressed against said coated side, and caused to travel with the blue print paper. In the modified form of the device, the moist absorbent material forms an outer layer on a roller and the coated side of the paper passes over the roller facing inwardly instead of outwardly, and hence is in contact with the absorbent surface of the roller. Thus in both cases, the exposed surface is brought into direct contact with the blotting material, and travels therewith without slipping relatively thereto. In the drawings (Fig. 5), 71 indicates the roller having a felt or other absorbent covering 78 and mounted to dip in a suitable tank 79, the water level in which is controlled by an overflow pipe, as previously described. A spray of water from a pipe 80 is directed upwardly against the lower part of the roller to wash the chemical therefrom in addition to the washing that the roller receives in turning with its lower part submerged in the water bath.

The operation described in connection with the apparatus of Figs. 4 and 5 might be called a mechanical method of applying moisture to the surface of a blue print and removing the loose, exposed chemical as well as the underexposed chemical therefrom and without the possibility of any migration of the blues into the whites.

I claim:

1. The method of making non-bleeding photo-prints comprising coating a sheet of water-permeable material with a ferricyanide of an alkali metal and a light sensitive ferric ammonium compound of an organic acid, exposing portions of the coated surface to light, applying water to the rear surface only of said sheet to initiate oxidation without causing encroachment of the chemicals in the reduced areas upon those in the unreduced areas, applying a water wash to said sheet after a time interval sufficient to insure such oxidation, and thereafter subjecting the same to a stronger oxidizing agent.

2. The method of making non-bleeding blue-prints comprising coating a sheet of water-permeable material with a ferricyanide of an alkali metal and a light sensitive ferric ammonium compound of an organic acid, exposing portions of the coated surface to light, applying a puddle of water to the upper surface only of said sheet when the same is traveling substantially horizontally in inverted position, whereby the water soaks through said sheet and starts initial oxidation without causing running of the blue color into the white areas.

3. The method of making non-bleeding blue-prints comprising coating a sheet of water-permeable material with a ferricyanide of an alkali metal and a light sensitive ferric ammonium compound of an organic acid, exposing portions of the coated surface to light, passing said sheet over a moistened roller with the coated side up-
permost, whereby the moisture permeates said sheet and initiates oxidation without causing running of the blue color into the white areas.

4. The method of making non-bleeding blue-prints comprising coating a sheet of water-permeable material with a ferricyanide of an alkali metal and a light sensitive ferric ammonium

compound of an organic acid, exposing portions of the coated surface to light, pressing the uncoated side of said sheet against a surface moistened with water, whereby the moisture soaks through said sheet and reacts with the chemicals thereon without causing running of the blue color into the white areas.

5. The method of making non-bleeding blue-prints comprising coating a sheet of material with a ferricyanide of an alkali metal and a light sensitive ferric ammonium compound of an organic acid, exposing portions of the coated surface to light, pressing the coated side of said sheet against a sheet of absorbent material moistened with water, and separating the two without sliding one on the other, whereby the loose outer layer of chemicals is removed by said absorbent material without causing running of the blue color into the white areas.

6. The method as in claim 5 with the added steps of washing the said removed chemicals from said absorbent sheet and thereafter recontacting said absorbent sheet with said coated side, and repeating the cycle of operations indefinitely.

7. The method as in claim 5 in which the chemicals removed by said absorbent material are thereafter removed from said absorbent material to permit reuse of the latter.

8. The method of making non-bleeding blue-prints comprising coating a sheet of material with a ferricyanide of an alkali metal and a light sensitive ferric ammonium compound of an organic acid, exposing portions of the coated surface to light, pressing the coated side of said material against a moving layer of moistened absorbent material while said sheet is traveling therewith, and thereafter separating said sheet and said layer, whereby oxidation of the exposed portions is begun during said contact and removal of the chemicals from the unexposed portions of said surface is effected.

9. The method as in claim 8, in which said removed chemicals are washed from said moving layer of absorbent material by passing the same through a bath, and thereafter again bringing said layer into contact with the coated side of said traveling sheet, in a continuous operation.

10. The method of making non-bleeding blue-prints comprising coating a sheet of water-permeable material with a ferricyanide of an alkali metal and a light sensitive ferric ammonium compound of an organic acid, exposing portions of the coated surface to light, applying water to the rear surface only of said sheet and applying water vapor to the coated surface of said sheet, to initiate oxidation without causing encroachment of the chemicals in the reduced areas upon those in the unreduced areas, subsequently applying a water wash to said sheet and thereafter subjecting the same to a stronger oxidizing agent.

11. The method of developing an exposed light-sensitized layer comprising a ferricyanide of an alkali metal and a light sensitive ferric ammonium compound of an organic acid, in close and relatively immovable contact with an absorbent layer of material, which consists in applying water to said absorbent layer whereby the moisture held thereby is supplied to the dry sensitized layer substantially evenly in small quantities, sufficient to start oxidation, but insufficient to cause migration of the chemicals in the reduced areas into the unreduced areas.

12. The method of developing exposed blue-print paper, which comprises the step of moisten-

- ing the paper, by capillary attraction of fibers near the exposed surface, by means of water in a moist capillary medium more remote therefrom.
13. The method of developing exposed blueprint paper, which comprises the step of moistening the chemical bearing portions of the exposed paper with an evenly distributed amount of water insufficient to supersaturate the paper.
14. The method of making blueprints, comprising coating a sheet of material with a light sensitive compound, exposing portions of the coated surface to light, pressing the coated side of the dry sheet against a sheet of absorbent material moistened with a developer, separating said two sheets without sliding one on the other, whereby loose chemicals are removed by said absorbent material without causing running of the areas of one shade into areas of a different shade, and removing said chemicals from said absorbent material, whereby the latter may be reused without staining the prints.

15. The method of making blueprints which comprises coating a sheet of material with a light sensitive compound rendered insoluble in water by exposure to light, exposing portions of the coated surface to light, contacting the coated side of the unmoistened material with a layer of moistened, absorbent material traveling in an endless circuit, said sheet moving with said traveling, absorbent material during part of said circuit without slipping thereover, separating said sheet and said layer, whereby development of the exposed portions is begun during said contact and removal of the chemicals from the unexposed portions of said surface is effected by said contact and separation, and removing said chemicals from said absorbent material, whereby the traveling, absorbent material may be used continuously.

HAROLD J. BRUNK. 20
